UNITED STATES PATENT OFFICE.

JOSEPH R. BLAINE, OF OAK PARK, ILLINOIS, ASSIGNOR TO CLEM E. WHEELER, OF CHICAGO, ILLINOIS.

FOLDING AND AUTOMATICALLY-CLOSING DESK ELEMENT.

Application filed July 23, 1927. Serial No. 208,007.

The purpose of this invention is to provide a convenient form of office desk having a receptacle for papers which is upright at the working position and forwardly open for receiving papers, and adapted to be folded to horizontal position upon the top of the desk, and in the process to be closed for securely retaining the papers therein, and which is adapted to be securely locked at its upright working position releasably for permitting it to be closed as indicated. The invention consists in the elements and features of construction shown and described as indicated in the claims.

15 In the drawings:—

Figure 1 is a vertical fore-and-aft section of the top or work table of the desk equipped with this invention which is shown in vertical section at open working position, the parts being shown in full line at working position and in dotted line at closed position.

Figure 2 is a detail section at the line 2—2 on Figure 1 showing the catch device for locking the receptacle at upright working position.

Figure 3 is a detail section at the line 3—3 on Figure 1.

Figure 4 is a detail section at the line 4—4 on Figure 3.

30 Figure 5 is a detail section on an enlarged scale of part of what is shown at the lower end of Figure 2.

In the drawings the top of the desk, hereinafter referred to in relation to the receptacle as the support, is shown at A, being a stamped metal member as may be understood from the section, rudiments of the supporting standards of the desk being indicated at B. B. C is a receptacle for papers also made of metal stampings as may be understood by the section. The receptacle C is hingedly mounted by the forward lower corner upon the desk top or support, A, as indicated at a, and is provided at the rear lower corner with the means for releasably locking it at upright position by engagement of its said rear lower corner with the support by means of catch devices indicated in totality at D, and herein-after more particularly described. The receptacle, C, is open at its forward side toward the working area of the desk top or support, A, as indicated at C¹, and an appurtenant member which in the form illustrated is a partial closure or guard for this open side, is provided in the form of a collapsible device, E,

which is pivotally mounted on the receptacle as seen at e, and adapted to swing forwardly to position shown in full line in Figure 1 for affording access over its upper edge to said device and to the receptacle, said device, E, being formed with lateral flanges, E², E², with lapping extensions, e², rendering it channel-form, so that the papers inserted into its upper end over its upper edge between the flange sides are safely guided into and retained in said device and in the receptacle. The pivot, e, is positioned with respect to the receptacle and with respect to the flanges, E², of the closure member, E, so that when the latter is tilted about said pivots to upright position of its forward side, said forward side is a little back of the plane of the forward edges of the opposite ends of the receptacle as indicated by dotted line position of said closure at the closed and folded position of the receptacle in Figure 1. For normally checking and holding the appurtenant device at the open or expanded position shown in full line in Figure 1, and permitting it to swing to the collapsed or receptacle-closing or guarding position shown in dotted line in that figure, and for actuating it from one position to the other in the folding movement of the receptacle from upright position of service to the prone position lodged flat upon the desk top or support, as shown in dotted line in Figure 1, there is provided at either end, and if desired, at both ends, (though shown only at one end in the drawings) a cam device which comprises a slotted cam plate, F, mounted as a bracket upon the forward side of the appurtenant member, E, and extends through a slot, a¹, in the desk top or support, A, said cam plate having its slot, f, engaging an abutment, preferably a stud-and-roll, G, which is mounted rigidly in the marginal flange, A¹, of the support or desk top, A. The position of this bracket cam plate, and co-operating stud-and-roll abutment, and the form of the slot in the cam bracket, are selected and designed in view of the relative positions of the hinge pivot of the receptacle to the support at a, and the pivot of the member, E, to the receptacle at e, so that in the folding movement of the receptacle from upright toward prone position, the inclination of the member, E, from full line position shown in Figure 1 shall not be materially altered during the initial folding movement of the receptacle through the angle of inclination of said mem- 110

ber; so that by the time the receptacle has been tilted forward through an angle corresponding to the inclined position of the collapsible guard member, E, at the working position of the parts, the member, E, is entirely within the receptacle, as indicated in dotted line at the prone position of the parts; and throughout the remainder of the folding movement of the receptacle to its prone position the two parts move substantially together. For effecting the movement as described, the form of the cam slot is as seen in Figure 1, comprising what may be termed the initial part, 20, substantially parallel with the support, A, at that upright position of the receptacle, and the final part, 21, curved in an arc of a circle about the pivot, a, at the folded down or closed position of the receptacle. It will be obvious that the form and direction of the part 20 of the cam slot is not necessarily precisely as shown, that is, is not necessarily precisely parallel with the support, A, nor necessarily perfectly straight, it being only necessary that it shall be at such an angle to the face of the member, E, as to afford the necessary camming action for rocking said member about its pivot, e, that is, relatively to the receptacle, substantially as fast as the angle of inclination of the receptacle changes in its initial tilting movement for closing. But the arcuate form of the part, 21, of the slot, as described, is obligatory in order that the relative position of the appurtenant member, E, and receptacle shall not be changed, but the two shall move together about the pivot of the hinge, a, throughout the portion of the folding movement of the receptacle after by the initial tilting of the receptacle, the member, E, is in collapsed and closed or in guarding relation thereto.

For locking the receptacle at working position, that is, standing upright on the work support with the appurtenant closure member at open position, there is provided a locking means which comprises a catch device at the rear lower corner of the receptacle, said catch device consisting of a catch plate, 30, mounted on the support, A, having a slot, 31, for engagement of a catch nose, 32, of a lever catch member, 33, which, as shown, is in the form of a bell crank lever fulcrumed at 34 on the rear wall, C², of the receptacle, C, the catch nose, 32, being formed for protruding into and through the slot in the catch plate when the receptacle is swung to upright position, the hook, 32^a, of said catch nose engaging under the edge of the catch plate at the end of the slot 31, the means for causing such engagement being a stretched spring, 35, which is connected at one end to the horizontally projecting arm, 33^a, of the bell crank lever, 33, and at the other end to a pressure member, 40, which is mounted slidingly on the back wall, C², the pivot, 34, serving as one guide for the sliding movement, and a second guide being

formed by a similar stud, 34^a, the member, 40, having slots, 41, for engaging the studs for said sliding movement. The lower end of the pressure member, 40, is curved in the arc of a circle as seen at 42, and dimensioned for being stressed by the spring, 35, onto the upper side of the catch plate 30 directly over the engagement therewith of the hook, 32^a, for reinforcing the engagement of the hook with the catch plate. A link, 50, slotted at its lower end as seen at 51 for engaging the horizontal arm, 33^a, of the bell crank lever, 33, extends up through the receptacle to the upper end thereof where it is connected with the manually operated lever, 52, fulcrumed at 53 intermediate its ends on a pocket hereinafter described, which is mounted on the receptacle wall, the shorter arm affording the pivotal connection at 54 with the upper end of the link, and the longer arm serving as an operating handle. At the position of the bell crank lever at which the catch nose thereof is engaged with the catch plate, 30, the longer arm of the lever, 52, extends horizontally, and there is provided for accommodating said lever and affording convenient means for fulcruming it, a pocket member, 56, marginally flanged as seen at 57 and inserted through an aperture in the top of the receptacle, the flange being stopped upon the upper side of said top, and said pocket member having at the lower rear corner slots in its bottom and rear wall as seen at 58 for accommodating the short arm of the lever and the connected end of the link, 50, as seen in Figure 1. Desirably, the entire locking construction described is partitioned off from the filing space of the receptacle by a vertical partition, C³, which may extend high enough to guard against the entanglement with the parts of the locking device of papers inserted as indicated over the upper edge of the closure, E. Desirably, to prevent accidental entrance of extraneous matter into the space partitioned off as described for the locking device, the slot, 30^a, of the catch plate is provided with a closure, shown at 60, hinged to the under side of said catch plate and provided with a spring, 61, coiled around its pivot and reacting for stressing said closure upward against the under side of the catch plate to closed position over the slot. This closure is encountered and pushed open by the end of the catch nose, 32, when the latter is intruded through the slot in swinging the receptacle to upright position, and the closure thus does not interfere with the engagement of the catch nose with the edge of the slot in the catch plate as described.

The part, 40, having the segment terminal, 42, above described as a pressure member adapted to be stressed against the catch plate for preventing accidental disengagement of the catch nose, 32, with the catch plate, performs an additional function in the absence or deficient functioning of the closure member,

60, namely, that when the receptacle is at closed position flat upon the desk top, as in dotted line position in Figure 1, in the absence, or defective action, of the closure, 60, 5 the catch nose, 32, projecting rearwardly might be liable to accidental engagement by any loose pendant draperies of persons having occasion to pass by the desk at the rear, which possible casualty is prevented by the 10 protrusion of the part, 32, under the stress of the spring, 35, to the position shown in full line in Figure 4, where it completely laps and guards the catch hook, 32^a, of said catch nose.

I claim:—

15. 1. In a construction of the character indicated in combination with a support and a receptacle hingedly mounted thereon, and at one position extending upright therefrom, said receptacle being open forwardly, an appurtenant member adapted for guiding said forward opening, hingedly connected with the receptacle for swinging into guarding position at the forward opening of the receptacle, and means controlling the relative 20 movements of the receptacle and said appurtenant member, comprising co-operating parts, one of which is mounted in fixed position on the support and the other is fixed on and with respect to the appurtenant member. 25
30. 2. In a construction of the character indicated in combination with a support and a receptacle hingedly mounted thereon, and at one position extending upright therefrom, adapted to be folded forwardly from said 35 position for lodgment on the support, said receptacle being open forwardly; an appurtenant member mounted collapsibly with respect to the receptacle in the forward opening of the latter, and means for controlling 40 the relative movements of the receptacle and said collapsible appurtenant member consisting of a slotted cam plate and a co-operating abutment, one of said co-operating parts being mounted on the support and the other 45 carried by said appurtenant member, said cam plate and abutment being relatively positioned, and the cam slot being shaped for causing the appurtenant member to be moved collapsibly with respect to the receptacle in 50 a limited initial part of the movement of the receptacle away from upright position, the remainder of the cam slot being shaped, for holding said appurtenant member in collapsed position during the remainder of the 55 movement of the receptacle to lodged position.
3. In a construction of the character indicated in combination with a supporting member, a forwardly open receptacle hingedly mounted thereon for swinging forwardly from substantially upright position to lodgment upon the support; an appurtenant member adapted for guarding the forward opening of the receptacle hingedly connected to 60 the latter for movement into and out of said 65 guarding position; means controlling the relative movement of the receptacle and the guarding member consisting of a slotted cam plate and a co-operating abutment, one of said co-operating parts being mounted on the support, and the other on the guarding member, said parts being relatively positioned, and the cam slot being formed, for moving the guarding member into guarding position in a limited part of the initial forwardly tilting movement of the receptacle away from upright position. 70
4. In a construction of the character indicated in combination with a support and a receptacle hingedly mounted thereon for extending upwardly therefrom, means for releasably locking the receptacle at upright position, comprising a catch plate mounted in the support below the receptacle toward a side thereof relatively remote from the hinge; a co-operating catch member mounted on the rear side of the receptacle at said lower end thereof; an operating link from said co-operating catch member extending past the receptacle cavity to the top of the receptacle, and manually accessible and operable means at the top of the receptacle for actuating said link for releasing the catch. 75
5. In a construction of the character indicated comprising a support and a receptacle hingedly mounted thereon for extending upwardly at operative position, the receptacle being hinged to the support at the lower forward edge of the receptacle; means for locking it at upright position mounted at the lower end of the receptacle rearward of the hinge, said means comprising co-operating members mounted respectively on the support and on the receptacle for engagement of each other at upright position of the receptacle, one of said members being spring-actuated for engaging it with the other; a link extending from said spring-actuated member to the upper end of the receptacle, and means at said upper end for operating said link to disengage said co-operating members. 80
6. In a construction of the character indicated comprising a support and a receptacle hingedly mounted thereon for extending upwardly at operative position, the receptacle being hinged to the support at the lower forward part of the receptacle; means for locking it at upright position, mounted at the lower end of the receptacle rearward of the hinge line, said means comprising co-operating members mounted respectively on the support and on the receptacle for engagement of each other at upright position of the receptacle, one of said members being spring-actuated for engaging it with the other; an auxiliary member movably mounted on the receptacle; a spring connecting said two last-mentioned members for holding the spring-actuated member in engagement with the co-operating member which is carried on the support. 85
- 130

port, and for holding the second of said members stressed toward the area of engagement of said members with each other; a link extending from the spring-actuated member to the upper end of the receptacle, and means at said upper end for operating said link to disengage said co-operating members.

7. A structure of the character indicated comprising a work support and a receptacle 10 hingedly mounted thereon for extending upright at position for receiving contents, and folding down forwardly for lodgment on the support; means for releasably locking the receptacle at upright position, comprising co-operating catch members carried respectively by the support and the receptacle at the lower end of the latter rearward of its hinge; a pressure member carried by the receptacle formed and mounted for movement over the interlocked parts of the co-operating catch members for pressing them together at their engaged position; a spring reacting between the pressure member and the catch member which is mounted on the receptacle in the direction 25 for yieldingly holding the catch member in engaged position, and holding the pressure member against said catch member, and manually operable means for disengaging the catch members.

30 8. A structure of the character indicated comprising a work support and a receptacle hingedly mounted thereon for extending upright at position for receiving contents, and folding down forwardly for lodgment on the support; means for releasably locking the receptacle at upright position, comprising a catch plate on the support and a lever catch member fulcrumed on the receptacle having one arm formed with a catch hook for engaging the catch plate; a link operatively associated with the lever catch member for moving it out of catch-plate-engaging position against the reaction of the spring, and manually operable means for operating said link.

35 9. A structure of the character indicated comprising a substantially horizontal support and a receptacle hingedly mounted thereon extending upwardly from its hinge pivot and adapted to fold down forwardly from upright position; means for releasably locking the receptacle at one position within the range of said folding movement, said means comprising a receptacle at one of said positions comprising a catch plate on the support and a lever catch member fulcrumed on the receptacle having one arm formed with a catch hook for engaging the catch plate; a spring reacting on said lever for holding it normally in catch-plate-engaging position, and a link connected to the lever extending along the receptacle to the end opposite that at which it is hinged to the support and exteriorly accessible; manually

operable means for actuating the link for disengaging the catch hook.

10. A structure of the character indicated comprising a work support and a receptacle hingedly mounted thereon for swinging between two positions; a slotted catch plate carried by the receptacle, a catch member fulcrumed on the receptacle having one arm provided with a catch hook for engaging the catch plate, a spring reacting on the catch lever for holding the catch normally in catch-plate-engaging position; manually operable means extending to the exterior of the receptacle for disengaging the catch hook from the catch plate, and a movably mounted 70 spring-stressed device on the receptacle for engaging the catch plate at the opposite side from that at which the nose of the catch hook engages the same for reinforcing the engagement of the catch plate. 75 80 85

11. In a structure of the character described comprising a work support and a receptacle hinged at its lower end to said support for folding down thereon, and exposing 90 said lower end, a catch device for engaging the receptacle to the support at upright position comprising a pivoted member having a catch nose and a spring re-acting on said member for stressing the catch nose in the direction for engagement with a co-operating element on the support, a guard member mounted for sliding longitudinally of the catch nose and dimensioned at one end for lapping and guarding the catch hook thereof, said spring being connected for said re-action 95 between the catch member and the guard for holding the guard member normally in guarding position over the catch hook. 100

12. In a construction of the character indicated in combination with a substantially 105 horizontal support and a receptacle hingedly mounted thereon and adapted at working position to extend upright therefrom and open forwardly; and an appurtenant member mounted collapsibly with respect to the receptacle at the forward opening of the latter, and means for controlling the relative movements of the receptacle and said collapsible appurtenant member, consisting of a slotted cam plate and a co-operating abutment, one of said co-operating parts being mounted on the support and the other carried by said appurtenant member, the initial first-acting part of the cam slot at the upright position of the receptacle extending 115 at a substantial angle to the chord of an arc about the hinge pivot of the receptacle, and the final last-acting portion of said slot at the collapsed position of the appurtenant member extending in an arc about said hinge pivot. 120 125

In testimony whereof, I have hereunto set my hand at Chicago, Illinois, this 7 day of July, 1927.

JOSEPH R. BLAINE.
